(57) **CLAIM**

I claim, the ornamental design of an LED open sign with neon appearance, as shown and described.

DESCRIPTION

This invention is intended for use as an “open sign” and can be used in both outdoor and indoor applications.

FIG. 1 is a perspective view of a LED open sign with neon appearance.

FIG. 2 is a front view.

FIG. 3 is a rear view; and,

FIG. 4 is a front view of the lit portion only.

In the drawings, the broken lines represent environmental structure forming no part of the claim.
